COIN-CONTROLLED MAGAZINE SWITCH
MECHANISM

Theodore M. Wright, North Tonawanda, N. Y.,
assignor to The Rudolph Wurlitzer Company,
North Tonawanda, N. Y., a corporation of Ohio

Application February 17, 1938, Serial No. 191,041

9 Claims. (Cl. 200—52)

This invention relates to certain new and useful improvements in coin-controlled devices adapted for use with coin-operated machines, such for example as phonographs, in which a predetermined number of records may be played upon the deposit of one or more coins.

It has for one of its objects to provide a coin-controlled device which is so designed and constructed as to function with coins of different denominations, say five and twenty-five cent pieces.

Another object of the invention is to provide a coin-controlled device of this character designed for use in conjunction with a magazine switch device and wherein the coin-controlled device mechanically controls the actuation of the magazine switch device to thereby properly register and govern the magazine switch in accordance with the coin-value deposited.

A further object is to provide a coin-controlled device of this character with means for adjusting the throw of one of the magazine controlling levers, thus permitting the coin-controlled device to be readily adaptable to operate with coins of different denominations, say, five, ten and twenty-five cent pieces.

A still further object of the invention is to provide a coin-controlled device which is simple, compact and inexpensive in construction, which is positive and efficient in operation and whose parts are not liable to get out of order.

Other features of the invention reside in the construction and arrangement of parts herein-after described and particularly pointed out in the appended claims.

In the accompanying drawings:

Figure 1 is a top plan view, partly in section, of a phonograph-chassis showing my coin-control device operatively associated therewith. Figure 2 is a fragmentary top plan view of the coin device embodying my invention. Figure 3 is a transverse vertical section taken substantially on line 3—3, Figure 1. Figure 4 is a front view, partly in section, of the lever mechanism actuated by the coin slides. Figure 5 is a fragmentary top plan view, partly in section, of the leverage mechanism associated with the nickel coin slide for actuating the magazine switch mechanism one step for each nickel deposited. Figure 6 is a fragmentary transverse vertical section taken on line 6—6, Figure 1. Figure 7 is a vertical section of the ratchet and levers for opening and closing the magazine switch. Figure 8 is a fragmentary vertical section taken in the plane of line 8—8, Figure 7. Figure 9 is a fragmentary

distended perspective view of the switch-controlling ratchet wheels and their associated pawls.

Similar characters of reference indicate corresponding parts throughout the several views.

5 While my coin-controlled device is applicable for use with various types of coin-operated machines, it has been designed more particularly for use on automatic phonographs which employ magazine switch mechanism for registering the coins deposited and which assure the playing of as many records as there are coins or coin-values deposited. In its general organization, it consists of the usual and well known coin-advancing slides, two being shown side by side as a complete unit on a suitable frame or support, for receiving, say, five and twenty-five cent pieces, respectively; mechanical means controlled by the respective coin slides for individually controlling the magazine switch mechanism in accordance with the value and number of coins deposited to maintain the circuit of the phonograph closed until the proper number of records have been played for the coins or coin-value deposited; and a resetting mechanism actuated by a moving part 10 of the phonograph and operatively connected to the magazine switch mechanism for opening the magazine switch to thereby open the circuit of the phonograph and restore the parts to their normal position.

15 Referring now to the drawings, the numeral 10 indicates the chassis of a phonograph upon which the working parts of my invention are mounted. Suitably mounted in a frame or support is a unit of coin slides indicated generally at 11 of well known construction to accommodate, say, five and twenty-five cent coins, the advancing slides of the unit being indicated at 12 and 13, respectively. In Figure 1 there is shown a portion 20 of the operating mechanism of an automatic selective phonograph which, however, forms no part of the present invention.

25 Mounted on a plate 14 secured to the chassis-base are a plurality of coin-slide controlled mechanisms, two being shown in the drawings and indicated generally at 15 and 16 for actuation by the five and twenty-five cent coin slides 12 and 13, respectively, for in turn individually governing the magazine switch mechanism. These slide-actuated mechanisms are identical in construction and a description of one of them will suffice for both. This mechanism consists of superposed, horizontally-swinging control arms or levers 17, 18 pivoted to swing about a common pivot 19 mounted on the plate 14 below the plane 30 of travel of the coin slides. Rising from adja-

35

40

45

50

55

cent the outer end of the top lever 18 is a post or pin 20 which is disposed normally in the sliding plane or path of the companion coin slide 12 or 13 to be actuated thereby to swing said levers 17, 18 to a position for controlling the magazine switch mechanism in accordance with the value or number of coins deposited in the coin slide. These levers are normally latched to swing jointly when advanced by a respective coin slide and a spring 21 constantly urges the lever 18 to a retracted position, shown in Figure 1, when the coin slide is retracted after discharging a coin. Pivoted at 22 to the lever 18 is a trip arm or latch 23 having a finger 24 at one end which normally abuts or latches behind an upstanding shoulder 25 formed on the control lever 17, as shown in Figure 2 in connection with the slide 12, and at its other end the latch has a spring 26 connected thereto which urges it against the post 20 rising from the lever 18. In advancing the coin slide 12 or 13 to its coin-discharging station, the slide strikes the post 26 of the corresponding control lever 18 and swings it and the companion latched lever 17 about the pivot 19 as a unit from the dotted line to the full line position shown in Figure 2 in connection with the slide 13, and as the parts near the end of the stroke, as seen by full lines in Figure 5, the finger 24 of the latch 23 is released from the shoulder 25 of the lever 17 through the medium of a cam finger 27 formed on the latch and striking a tappet-pin 28 arranged in its forward path and rising from the plate 14, thus automatically unlatching and releasing the lever 17 from the companion lever 18 and permitting the free and independent return of said lever 17 to its initial position in the manner which will hereafter appear. Upon the retraction of the coin slide to its initial position preparatory to inserting another coin, the lever 18 follows back with it under the pressure of its spring 21 and the latch 23 is automatically restored to its latched position behind the shoulder 25 of the lever 17 by the spring 26, thereby resetting these parts for the next coin slide operation.

A coin register and magazine switch 29 of the micro or like type is included in the circuit of the phonograph or other instrument and is rendered operative in response to the coin slide controlled mechanisms 15 and 16 to effect the closing of this switch, the latter remaining closed over a predetermined period in accordance with the number or value of the coins deposited in the coin slides. This switch includes a fixed contact 30 and a spring-pressed movable contact 31 adapted to be actuated by a rock arm 32 to effect the opening and closing of the switch. As shown in Figure 1, these contacts are connected to the motor 33 of the phonograph. Loosely mounted on an upright shaft 34 fixed to the chassis 10 of the phonograph adjacent the switch 29 are superposed ratchet wheels 35 and 36 disposed in spaced relation, as seen in Figures 3 and 7. Borne by and pivoted at 37 to the underside of the lower ratchet wheel 36 is a switch-governing element 38 which is shaped intermediate its ends to freely straddle or embrace the shaft 34 and is free to be displaced about its pivot in a direction axially of the shaft. The intermediate portion of this switch-governing element is adapted through the medium of an interposed washer 39 to abut against the free end of the switch-actuating arm 32, whereby when the element 38 is displaced in a direction away from the ratchet wheel, as seen by dotted lines in Figure 7, it serves to open the

switch 29, and when shifted in the opposite direction by spring pressure to the full line position seen in the same figure, the switch is automatically closed. As shown in Figure 7, the spring-pressed switch contact 31 tends constantly to seek a closed position, and this also tends to rock the arm 32 and switch-governing element 38 to the full line position shown in such figure. At its free end the switch-governing element 38 is provided with an upwardly-extending lug 40 which passes freely through an opening 41 in the lower ratchet wheel 36, the terminal end of this lug being beveled or pointed as indicated at 42 in Figure 8. Mounted on the upper ratchet wheel 35 in opposing relation to and for predetermined cooperative engagement with the beveled end of the lug 40 of the switch-governing element 38, is a tooth or projection 43 which, during relative movements of the ratchet wheels 35 and 36, in one instance, contacts said lug 40 to displace the switch-governing element 38 to switch-opening position and which, in another instance, is released from such contact to permit the automatic displacement of such element to switch-closing position. The ratchet wheels are mounted for independent rotation in a counter-clockwise direction, the upper wheel 35 being adapted to be actuated one step or one tooth for each five cent coin value deposited in one or the other of the coin slides 12, 13 during which time the companion or lower ratchet wheel 36 is stationary, and for each five cent coin value deposited the upper wheel 35 with its tooth or projection 43 progresses or recedes step by step away from the lug 40 of the companion switch-governing element, thereby registering the coin value and maintaining the circuit of the phonograph closed as determined by the coin value deposited. After each record is played on the phonograph, a moving part thereof functions to transmit a step by step counter-clockwise movement to the lower ratchet wheel 36 while the companion ratchet wheel 35 remains stationary so that eventually, after the playing of the last record of the number to be played for the coin value deposited, the beveled lug 40 of the switch governing element 38 will contact and ride beneath the companion tooth 43 of the upper ratchet wheel 35 and cause the displacement of such element to in turn rock the arm 32 to open the switch 29.

The counter-clockwise movement of the upper or coin-registering ratchet wheel 35 is mechanically controlled from one or the other of the mechanisms, 15, 16 associated with the five and twenty-five cent coin slides 12 and 13, respectively, so that for every five cent coin deposited the ratchet wheel 35 will be advanced one tooth and for every twenty-five cent coin deposited the ratchet wheel will be advanced five teeth to accordingly close the switch 29 which thereupon remains closed until the last record for the coin value deposited has been played. For this purpose there is associated with the control lever 17 of the five cent coin control mechanism, a reciprocating bar or link 44 pivoted at one end, as indicated at 45, to such lever, and having at its other end a spring-urged pivoted dog 46. A spring 47 connected to this reciprocating bar constantly tends to urge said bar to a retracted or effective operating position shown by dotted lines in Figure 5, while a spring 48 connected to the dog 46 urges the latter against a stop 49 applied to the base 10. Disposed at substantially right angles to the reciprocating bar 44 in end-wise cooperative engagement with the dog 46 is a

rock lever 50 pivoted intermediate its ends at 51 to the base 10 and provided at its other end with a pin 52 which extends upwardly through an arcuate slot 53 formed in the base 10, said pin normally abutting a spring-urged arm 54 pivoted at 55 to an adjoining bracket plate 56 on which the shaft 34 and associated parts are mounted. A spring 50a tends to urge the rock lever 50 to its full line position seen in Figure 5. This arm 54 is provided with a spring-pressed feed pawl 57 which engages the upper ratchet wheel 35 for turning it in a counter-clockwise direction in a step by step fashion. Upon the advancement of the coin slide 12, the bar 44 will be correspondingly advanced idly and the dog 46 will ultimately ride off the end of the rock lever 50 and be projected by its spring 48 into the path of the shoul- 10 dered portions 58 of such lever, so that upon the return of the bar 44 to its operative retracted position by its spring 47, after the completion of the advancing stroke of the coin slide and the subsequent unlatching of the control lever 17 from the companion lever 18 by the tappet 28, said dog 46 will trip the rock lever 50 and swing it from the full line to the dotted line position, shown in Figure 5, with the result that the feed pawl 57 will advance the ratchet wheel 35 one tooth.

In order to advance the coin-registering ratchet wheel 35 five teeth when a twenty-five cent coin is deposited in the coin slide 13, I provide a reciprocating bar or link 59 which is pivoted at one end at 60 to the control lever 17 of the mechanism associated with the coin slide 13, while its opposite end is pivotally connected to one arm of a rock lever 61 pivoted intermediate its ends at 62 to the base 10 and provided at its opposite end with a link 63 connected to one arm of a lever 64 loosely or pivotally mounted on the lower end of the ratchet wheel shaft 34. On its other arm this lever 64 carries a spring-pressed feed pawl 65 cooperating with the ratchet 35. A spring 66 connected to this pawl-carrying lever tends constantly to urge this lever and its associated parts including the reciprocating bar 59 and companion lever 17 from the full line to the dotted line position seen in Figure 2. By this construction, when the coin slide 13 is advanced the corresponding control mechanism 16 is actuated to in turn swing the lever 64 in a clockwise direction from the dotted line to the full line position shown in Figure 2. During this time the feed pawl 65 merely ratchets clockwise over five teeth of the wheel 35, and upon the completion of the advancing stroke of the coin slide the spring 66 restores the parts to their normal positions, the feed pawl at the same time actuating the ratchet wheel in a counter-clockwise direction a distance of five teeth.

A spring-pressed, duplex pawl 67 may be provided for engagement with both ratchet wheels 35, 36 to constitute a forward and backward stop for such wheels.

For the purpose of effecting the counter-clockwise movement of the lower ratchet wheel 36 to restore the switch 29 to its open position after the patron has received the playing of records corresponding to the coin value deposited, I provide a feed pawl 68 which is connected by a screw 69 and slot 70 to the bracket plate 56 for combined pivotal and sliding movement relative to the ratchet wheel. A spring 71 normally urges this pawl to swing in a direction toward the periphery of the wheel. This pawl is disposed for actuation to move the ratchet wheel 36 counter-

clockwise a distance of one tooth by a moving part of the phonograph, say the gear wheel 72 associated with the record-changing mechanism. To this end this gear has a lug 73 thereon which 5 at a predetermined time engages the end of the pawl and shifts it in a direction to turn the ratchet wheel one tooth, thereby moving the switch-governing element 38, 40 carried by it in a direction toward the tooth 43 on the coin-registering ratchet wheel 35. With each playing cycle of the phonograph the wheel 35 is moved in a step by step fashion until the lug 49 of the switch-governing element registers with the companion tooth 43 of the wheel 35, at which time 10 the switch 29 will be automatically opened, indicating that the last record for the coin value deposited has been played.

If it be desired to employ this mechanism in connection with a remote control coin slide, a 20 magnet 74 may be mounted on the plate 56 adjoining the five cent control pawl 57 and the carrying arm 54 of the latter may be provided with an armature 75, so that upon energizing the magnet the pawl is actuated to move the ratchet wheel 35 one step for each coin deposited.

Means are provided for adjusting the effective movement transmitted by the feed pawl 65 to the coin-registering ratchet 35, whereby a coin of different denomination may be used in the coin slide 13 and whereby a more or less number of records may be played, for the coin used. For this purpose I provide an adjustable cam plate 76 mounted on the shaft 34 in overlying relation to the upper ratchet wheel and adapted to be secured thereon in an adjusted set position by a screw 77. This plate is shaped to provide an edge contour 78 which is disposed within the pitch circle of the ratchet teeth of the wheel 35 so as to not interfere with the normal engagement of the pawl 65. As shown in Figure 3, the tooth-engaging end or lug 79 of this pawl is of a length to extend over the peripheral edge of the cam plate. At its outer end the cam plate has a portion 80 which extends over the adjoining toothed portion of the wheel to block out the teeth thereof from engagement by the feed pawl. As seen in Figures 1 and 2 of the drawings, the cam plate 76 is set to effect a pawl-ratcheting stroke of five teeth for registering five record 30 plays for each twenty-five cent coin deposited. Should it be desired, for example, to substitute a ten cent coin slide for the twenty-five cent slide, then the cam plate is adjusted in a clockwise direction to block out, say three teeth of the normally exposed five teeth of the ratchet wheel 35, so that for a portion of its initial or presetting travel in a clockwise direction the pawl 65 rides over the edge of the cam plate portion 80 a distance equal to three teeth and 40 then ratchets over two of the exposed teeth for the balance of its stroke. On the return or effective counter-clockwise stroke of the pawl 65, the ratchet wheel will be moved in a like direction a distance of two teeth, and for the balance of its return stroke the pawl will encounter the cam portion 80 and be lifted from the ratchet teeth and merely slide idly to its initial or starting position over a distance of three teeth as 50 determined by the stroke of the coin-slide actuated bar 59. Should it be desired that the patron receive three records plays for ten cents, then the cam plate is accordingly adjusted to block out all but three teeth of the normally exposed five teeth of the ratchet wheel 35.

Briefly, the operation of this coin-controlled mechanism is as follows:

Assume that the mechanism is applied to an automatic coin-controlled phonograph and the patron at five cents per record, desires to play six records and after making his selections at the phonograph, places a nickel in the slide 12 and a quarter in the slide 13. Upon advancing the slide 12, the ratchet mechanism 35, 57, through the slide-actuated mechanism 15 and intermediate parts 44, 46, 59 and 54, is advanced one tooth in a counter-clockwise direction and accordingly the lug 43 on the ratchet wheel 35 moves away a distance of one tooth from the tapered end 40 of the switch-governing element 38, thereby closing the magazine switch 29 and rendering the phonograph operative. Upon advancing the twenty-five cent slide 13, the ratchet mechanism 35, 65 is advanced five teeth in the same direction and in a like manner through the slide-actuated mechanism 16 and intermediate parts 59, 61, 63 and 64, and the lug 43 on the wheel 35 is accordingly moved the same distance away from the tapered end of the switch-actuating element 38. After each record is played the gear 72 having the lug 73 thereon, strikes the pawl 63 which engages the wheel 36 and likewise moves it in a counter-clockwise direction one tooth at a time until the tapered end 40 of the switch element 38 rides under or contacts the lug 43 on the ratchet wheel 35, at which time the magazine switch 29 is automatically opened. Upon the deposit of another coin in any one of the coin slides, the ratchet wheel 35 and lug 43 move away from the switch-governing element 38, 49 to automatically effect the closing of the switch 29 and start the phonograph playing.

Should a patron insert, during a given time interval, more coins or coin values than correspond to the number of teeth on the companion switch control ratchet wheels 35, 36, provision is made to prevent the opening of the switch 29 at a predetermined time in the relative coin-registering movements of the wheel 35, as for example, when the latter makes a complete revolution and the lug 43 approaches a position adjoining the tapered end 42 of the switch-actuating element 38. To this end, as shown in Figure 9, I provide a stop pin 81 rising from the top face of the wheel 36 and adjoining said tapered end of the element 38 at the trailing or clockwise-direction side of such end. This stop is disposed in the counter-clockwise path of travel of the lug 43 on the coin-registering wheel 35 to prevent that lug from contacting and tripping the switch-actuating element 38 should that wheel be advanced to that extent. When contact of the lug 43 is made with the pin 81, and coins are thereafter inserted in the coin slides, then both wheels 35, 36 are propelled in unison to properly register the coin value.

I claim as my invention:

1. A device of the character described, comprising a switch including a displaceable part to be actuated for controlling the opening and closing thereof, a plurality of relatively-movable ratchet wheels, relatively-engageable switch-governing elements applied to said wheels in cooperative relation with said displaceable switch-controlling part for governing the opening and closing of said switch in response to the wheel movements, one of said elements being displaceable by the companion element to govern the switch-

controlling part, a plurality of feed pawls operatively associated with one of said ratchet wheels for advancing it different predetermined distances to cause a displacement of the element borne thereto to a switch-closing position, means operatively connected to said feed pawls for independently actuating said pawls to advance said last-named wheel predetermined distances and means for actuating said other ratchet wheel at predetermined times to advance it relatively to the companion ratchet wheel in a direction to cause the element borne thereby to displace the companion switch-governing element to a switch-opening position.

15 2. A switch-controlling device of the character described, comprising adjoining, relatively movable ratchet wheels having juxtaposed elements thereon for controlling the opening and closing of the switch, said elements being engaged in switch-opening position and relatively displaced in switch-closing position, a plurality of independent ratchet feed means operatively connected with one of said ratchet wheels for moving the same relative to the companion wheel a predetermined distance to effect the disengagement and divergent displacement of the switch-controlling elements to close the switch and govern its duration of closure, and means for actuating said other ratchet wheel at predetermined times to advance the same in a direction to effect a convergent displacement of the switch-controlling elements to bring them to switch-opening position.

3. A switch controlling mechanism, comprising 35 a switch-governing member movable to and from a switch-closing position, adjoining, relatively-movable ratchet wheels having juxtaposed elements thereon for controlling said switch-governing member, said elements being engaged in switch-opening position and relatively displaced in switch-closing position, a plurality of feed pawls associated with one of said ratchet wheels and each in operative relation thereto to independently advance said wheel a distance of one or more teeth to effect the actuation of said 40 juxtaposed elements to switch-closing position, means operatively connected to said feed pawls for actuating them to advance the companion ratchet wheel predetermined distances, and means for actuating said other ratchet wheel a distance of one tooth at predetermined times in a like direction to bring said controlling elements into switch-opening position.

4. A device of the character described, comprising 45 a switch, a pair of ratchet wheels mounted for relative independent rotation and having feed pawl means associated therewith, switch-governing elements applied to said wheels, one of said elements consisting of a displaceable arm pivotally mounted on one of the ratchet wheels for controlling the opening and closing of the switch and the other consisting of a lug fixed on the companion ratchet wheel and disposed for governing the displaceable movements of said arm, means for actuating the feed pawl means of said lug-bearing ratchet wheel to move the lug from engagement with said arm to cause the closing of the switch, and means for actuating the feed pawl means of the companion ratchet wheel to move its arm into displaceable engagement with said lug to cause the opening of the switch.

5. A device of the character described, comprising 50 a switch, a pair of ratchet wheels mounted for relative independent rotation, switch-gov-

erning elements applied to said wheels, one of said elements consisting of a displaceable arm mounted on one of said wheels for controlling the opening and closing of the switch and the other consisting of a lug mounted on the other of said wheels for governing the displaceable movements of said arm, a plurality of feed pawls associated with one of said wheels for advancing it in one direction to close the switch, independent means corresponding in number to and operatively connected to said companion pawls, respectively, for imparting different degrees of movement to the associated ratchet wheel, and a feed pawl associated with the other ratchet wheel for advancing it at a predetermined time in a like direction a distance of one tooth at a time to bring said switch-governing elements to switch-opening position.

6. A device of the character described, comprising a switch, a pair of ratchet wheels mounted for relative independent rotation and having feed pawl means associated therewith, switch-governing elements applied to said wheels, one of said elements consisting of a displaceable arm for controlling the opening and closing of the switch and the other consisting of a lug disposed for governing the displaceable movements of said arm, means for actuating the feed pawl means of said lug-bearing ratchet wheel to move the lug from engagement with said arm to cause the closing of the switch, a stop element mounted on that wheel to which said displaceable arm is applied and disposed in the path of travel of the lug on the other wheel to prevent, at predetermined times, such parts assuming a switch-opening position, and means for actuating the feed pawl means of the arm-bearing wheel to move its arm into displaceable engagement with said lug to cause the opening of the switch.

7. A switch-controlling device of the character described, comprising adjoining relatively movable ratchet wheels having juxtaposed elements thereon for controlling the opening and closing of the switch, said elements being engaged in switch-opening position and relatively displaced in switch-closing position, a feed pawl for actuating one of said wheels to effect the disengagement and divergent displacement of the switch-controlling elements to close the switch and govern its duration of closure, means operatively connected to said feed pawl for transmitting an effective advancing stroke thereto and its companion ratchet wheel, means associated with said

actuated wheel and its pawl for adjusting the effective stroke of the pawl to advance said wheel a predetermined distance, said means including a cam plate disposed axially of such wheel and having a portion extending over some of its ratchet teeth to block out the same from engagement by the companion pawl, and means for actuating said other ratchet wheel at predetermined times to advance the same in a direction to effect a convergent displacement of the switch-controlling elements to bring them to switch-opening position.

8. In switch mechanism, a switch, means for governing said switch, and means for actuating the switch-governing means to close the switch, comprising a slide, a pair of superposed levers pivoted to swing in a plane parallel to the plane of movement of the slide, means for causing said levers to move simultaneously in one direction upon the advance stroke of the slide, an operative connection between one of said levers and said switch-governing means, and means rendered operative at the completion of the operative stroke of the slide for effecting the automatic release of said last-named lever from its companion lever and the return thereof to the initial position independently of the slide to actuate said connection and render the switch-governing means operative to close said switch.
9. In switch mechanism, a switch, means for governing said switch, and means for actuating the switch-governing means to close the switch, comprising a slide, a pair of superposed levers pivoted to swing in a plane parallel to the plane of movement of the slide, one of said levers having a projection thereon disposed in the path of the slide for actuation thereby on its advance stroke, latch means connecting the levers as a unit for causing said levers to move simultaneously on the advance stroke of said slide, an operative connection between the other of said levers and said switch-governing means, means for normally urging said last-named lever to its initial position, and means rendered operative at the completion of the operative stroke of the slide for effecting the automatic release of said other last-named lever from its companion slide-engaging lever and for causing the return thereof to its initial position independently of the slide to actuate said connection and render the switch-governing means operative to close said switch.

THEODORE M. WRIGHT.
